DESIGN FOR A SUN'S RAY DEMONSTRATOR

Leo G. Haase, Pasadena, Calif.

Application March 20, 1942, Serial No. 106,267

Term of patent 14 years

To all whom it may concern:

Be it known that I, Leo G. Haase, a citizen of the United States, residing at Pasadena, in the county of Los Angeles and State of California, have invented a new, original, and ornamental Design for a Sun's Ray Demonstrator, of which the following is a specification, reference being had to the accompanying drawing, forming a part thereof.

In the accompanying drawing, Fig. 1 is a top

plan view of a sun's ray demonstrator showing my new design;

Fig. 2 is a side elevation; and

Fig. 3 is an end view.

I claim:

The ornamental design for a sun's ray demonstrator, as shown.

LEO G. HAASE.
